UNITED STATES PATENT OFFICE.

MOSES H. FREEMAN, OF SOMERVILLE, MASSACHUSETTS.

IMPROVEMENT IN PIPE-TONGS.

Specification forming part of Letters Patent No. 59,582, dated November 13, 1866.

To all whom it may concern:

Be it known that I, MOSES H. FREEMAN, of Somerville, in the county of Middlesex and State of Massachusetts, have invented a new and useful Improvement in Pipe-Tongs; and I do hereby declare the same to be fully described in the following specification, and represented in the accompanying drawings, of which—

Figure 1 is a side view of them. Figs. 2 and 3 are edge views of their two jaw-levers as separated from one another.

In the said drawings, A and B are the two jaw-levers of the tongs, the first one being provided with a hook-jaw, a. The second—viz., B—has a tooth-jaw, b, the forms of such levers and jaws being as represented. There projects from the base of the jaw b a tooth, c, which, when the levers are crossed on one another, engages with one of a series, d, of notches made in the adjacent edge of the hook-jaw lever, or arranged therein as shown in the figures. A clasp, e, formed as shown in Figs. 1 and 3, extends from the lever B and projects over the lever A, it being simply to keep them together.

By setting the tooth c in either of the notches of the series d we constitute it the fulcrum of the two levers, and by means of the notches we can adjust the tooth-jaw nearer to or farther from the hook-jaw, as occasion may require.

The proper position of the tooth c for adjust-

ing the jaws to pipes or rods of different diameters may be indicated by figures or designating-marks engraved opposite the various notches of the series.

The two levers may be separated by drawing the hook-lever, or that marked A, lengthwise from between the tooth c and the clasp e of the lever, or that marked B. Thus it will be seen that the levers can easily be taken apart when it may be desirable to sharpen or grind the edge of the tooth b.

I do not claim a pipe-tongs made with one jaw adjustable relatively to the other; nor do I claim a pipe-tongs made as represented in the United States Patent No. 49,424, as with my pipe-tongs I have no slot extending through one of its levers, whereby the same is weakened; but I have the clasp e, the tooth c, and the jaw b to project from one side of the lever B, thereby avoiding the necessity of a slot and enabling the handles to be made large and strong.

What I claim is—

The arrangement of the clasp e, the tooth c, and the series d of notches with the two levers A B and their jaws a b, the whole being substantially as specified.

MOSES H. FREEMAN.
